UNITED STATES PATENT OFFICE.

LAWRENCE R. GOLLADAY, OF EAST PITTSBURGH, PENNSYLVANIA, ASSIGNOR TO
WESTINGHOUSE ELECTRIC & MANUFACTURING COMPANY, A CORPORATION OF
PENNSYLVANIA.

CASING FOR LIGHTNING ARRESTERS.

Application filed January 14, 1927. Serial No. 161,088.

My invention relates to electric protective devices, such as lightning arresters.

More particularly my invention relates to a novel lightning-arrester casing which is particularly adapted to be used with an arrester of the auto-valve type or with a protective device of any similar type which comprises a quantity of discharge material.

One of the objects of my invention is to provide a lightning-arrester casing having small external dimensions and a relatively large spark-gap chamber.

Another object of my invention is to provide a lightning-arrester casing which comprises means for securing and maintaining the spark-gap electrodes in definite spaced relation.

Still another object of my invention is to provide a lightning-arrester casing which comprises means for retaining discharge members within a discharge-gap chamber.

In the accompanying drawing, the single figure is a fragmentary view, partly in elevation and partly in section, showing a preferred embodiment of my invention.

A cylindrical porcelain casing 1 is provided with a lower cylindrical chamber 2 comprising a discharge-gap chamber in which are a set of disks or plates 3 of high-resistance material surmounted by a compression spring 4 holding the disks in intimate contact. A flexible strap member 5 of conducting material is provided for shunting current from the spring.

In the upper portion 6 of the casing is disposed a cylindrical spark-gap chamber 7 of larger diameter than the discharge-gap chamber and co-axially adjacent thereto, thereby forming a ledge 8 at the bottom of the discharge-gap chamber. A depending electrode 9 is disposed within the larger chamber and is connected to the casting by means of a stud-bolt 10 screwed into a projecting portion 12 of the cap 13 surrounding the device.

The ledge or seat 8 around the bottom of the upper chamber 7 is cut away to provide a central annular well or depression 14 having a second ledge 15 of smaller diameter. A porcelain disk-like partition member 16, separating the upper and lower chambers, is disposed within the well and is glazed to the face thereof. The partition member has a central perforation 17 in which an upwardly projecting electrode 18

is securely fastened, as by means of a stud-bolt 19.

Heretofore, auto-valve lightning-arrester casings have been provided with single chambers of uniform diameter in which both the disks and spark-gap electrodes were disposed, one on top of the other. The spark-gap electrodes were insecurely separated by means of a porcelain washer or collar which failed to maintain the spaced relation between the electrodes. This method of providing the gap was unsatisfactory, owing to the fact that, during transportation or installation of the lightning arrester, the electrodes occasionally slipped from their original positions to a spacing different from that which was most satisfactory for proper operation.

A means for securing the spark-gap electrodes rigidly to the casing has heretofore been greatly desired by workers in the art but no satisfactory method of so doing was developed, owing to the difficulties incident to the proper method of manufacturing such casings as have heretofore been used. The most satisfactory method of making porcelain lightning-arrester casings is by pugging or extruding and subsequently firing the material. While this method is most satisfactory, as to properties of the material, it is restricted as to the forms which may be made thereby. It is apparent that it would be extremely difficult to manufacture, by pugging, a casing having a partition such as has been hereinbefore described.

By my invention I provide a lightning-arrester casing which may be made by pugging, and thus retain all the characteristic advantages of material so made and which, in addition, will have a partition rigidly attached thereto.

In addition, by eliminating the spacing collar or washer, I am able to increase the effective internal diameter of the spark-gap chamber, as compared to smaller prior devices, thereby increasing the creepage distance between electrodes.

The porcelain disc-like partition member may be made from dry molded porcelain. Thus, any specified dimensions may be very accurately adhered to. By this method of mounting the spark-gap electrodes, any definite space relation may be obtained, and maintained throughout the life of the device.

Although I have described my invention

with respect to a specific embodiment thereof, it is apparent that it is not limited to the details shown, and I desire that the appended claims shall be accorded the broadest interpretation consistent with their wording and the prior art.

I claim as my invention:

1. A protective device comprising an excess-voltage discharging means and a series 10 protective spark-gap, a tubular casing having two adjacent co-axial chambers of different cross-sectional areas, thereby providing a shoulder, a disc-like partition member secured to the shoulder, a spark-gap electrode secured to the partition member and projecting into the chamber having the larger cross-sectional area, a cover member secured to the end of the casing which encloses said larger chamber, and a second spark-gap 20 electrode secured to the cover member and projecting into the larger chamber in spaced relation to said first-mentioned spark-gap electrode.
2. A protective device comprising an excess-voltage discharging means and a series 25 protective spark-gap, a porcelain tubular casing having two adjacent co-axial chambers of different cross-sectional areas, thereby providing a shoulder, a porcelain disc-like partition member glazed to the shoulder, a spark-gap electrode secured to the partition member and projecting into the chamber having the larger cross-sectional area, a cover member secured to the end of 30 the casing which encloses said larger chamber, and a second spark-gap electrode secured to the cover member and projecting into the larger chamber in spaced relation to said first mentioned spark-gap electrode, 35 said discharging means being disposed in the smaller chamber.

3. The combination with a lightning-

arrester casing having a concentrically disposed chamber which is enlarged abruptly at one end, thereby providing a shoulder, of a disc-like partition member secured to the face of the shoulder, and spaced spark-gap electrodes disposed within the enlarged portion of the chamber, one of said electrodes being secured to the partition member. 45

4. The combination with a tubular porcelain lightning-arrester casing having a concentrically disposed chamber which is enlarged abruptly at one end, thereby providing a shoulder, of a porcelain disk-like 50 partition member glazed to the face of the shoulder, spaced spark-gap electrodes disposed within the enlarged portion of the chamber, one of said electrodes being secured to the partition member, and discharge members disposed within the small portion of the chamber, said discharge members having the property of freely discharging currents only during the existence and continuance of excess-voltage conditions. 55

5. The combination with a tubular lightning-arrester casing having a spark-gap chamber containing two spark-gap electrodes spaced apart and a discharge-gap chamber co-axially adjacent thereto, opening into the 60 spark-gap chamber and containing a plurality of discharge elements, of a separate partition member interposed between the chambers and fastened to the casing, thereby securing one of the electrodes to the casing 70 and closing the opening between the chambers, and a cap closing the end of the casing which surrounds the spark-gap chamber, the second mentioned spark-gap electrode being secured to said cap. 75

In testimony whereof, I have hereunto subscribed my name this 10th day of January, 1927.

LAWRENCE R. GOLLADAY.
